UNITED STATES PATENT OFFICE.

JAMES T. GRIFFIN, OF WINDER, GEORGIA, ASSIGNOR OF FORTY PER CENT TO FLETCHER C. GRADDICK AND THIRTY-FIVE PER CENT TO HENRY C. HARGROVE, BOTH OF WINDER, GEORGIA.

BELT.

Application filed June 11, 1925. Serial No. 36,507.

REISSUED

This invention relates to an improved belt which is applicable to machinery generally but particularly intended for use with roving and analogous machines.

5 Heretofore it has been a difficult matter to provide a belt that had sufficient durability and resistance to meet the needs of heavy stress when used in connection with cones or cone pulleys, in view of the control lead and 10 delivery relatively to the cones from such heavy frames as are embodied in roving machines, and the belts heretofore used not only lacked the necessary wearing qualities but were also disadvantageously stretched 15 and thereby materially affected the resultant work.

The primary object of the improved belt, therefore, is to provide a device of the class specified which is particularly intended to 20 engage driving cones or cone pulleys of a roving frame wherein the usual stretching characteristics are reduced to a minimum and features of strength and durability embodied therein, to reduce the cost in the 25 use of belting.

A further object of the invention is to provide an improved belt that is superior to the ordinary leather belt or a belt formed of other flexible material alone, to replace the 30 usual form of belt just specified by a belt organization embodying a leather face member to engage the cones or cone pulleys which is reinforced by a rawhide or similar flexible material stitched to the back of the same 35 and an interposed endless chain link between the face and back members of the belt and held in central position, to positively resist stretching and also at the same time reinforce and strengthen the belt.

40 With the foregoing and other objects and advantages in view, the invention consists in the construction and arrangement of the several parts which will be more fully hereinafter described and claimed.

45 In the drawings:

Fig. 1 is an elevation of a portion of a roving machine, showing the cones or cone

pulleys with the improved belt applied thereto in its preferred use.

Fig. 2 is a plan view of a portion of the 50 belt on an enlarged scale and having parts thereof broken away.

Fig. 3 is a longitudinal section through the center of the improved belt, showing a portion thereof curved to illustrate the necessary 55 flexibility and the adaptability of the reinforcing chain link element to the curvature of the pulleys.

Fig. 4 is a transverse vertical section on the line 4—4, Fig. 2, showing the back member of the belt completed.

The improved belt comprises three essential elements 5, 6 and 7, the element 5 consisting of a leather strip of suitable dimensions, or a strip of analogous material, which 60 forms the base or bearing part of the belt and directly engages the surface of the cone or cone pulley or other rotating device with which the belt may be used. The element 5, however, is preferably formed of leather 65 and the element 6 consists of a strip of rawhide having the edges turned inwardly and secured by stitching or other fastening means as at 8 to the edge portions of the base member or bearing strip 5 of the belt, 70 as clearly shown by Fig. 4. By doubling the edges of the rawhide element or strip 6 inwardly, the said rawhide strip is elevated above the outer surface of the element or leather base strip 5 for the reception of the 75 element 7, which consists of a plurality of links 8, preferably of rectangular form, having at one end of each a joint knuckle or coupling member 9 with a transverse opening 80 therethrough to pivotally embrace or engage the adjacent end cross bar 11 of the next succeeding link, this structure being carried out through the whole length of the linked reinforcing element 7, said reinforcing element being in the form of a chain 85 belt of a length equal to the length of the improved belt organization. The rawhide backing or covering or element 6 extends over and bears snugly against the pivot

90

knuckles 9 and operates to hold the linked reinforcing element 7 in central relation between the elements 5 and 6, so that the several links will have freedom of action but at the same time be held against displacement, especially in view of the downwardly inclined portions of the rawhide backing or element 6 on opposite sides of the element 7. The element 7 will readily flex to conform to the curvature of the complete belt organization in traversing the cones or cone pulleys or analogous devices. By sloping the opposite portions of the element or rawhide backing 6 towards the edges of the element or bearing base 5 of the belt organization, lateral movement or displacement of the element 7 will be prevented. The element 7 composed of the connected links as explained is not in any other manner secured to the elements 5 and 6, and when the belt ends are connected to provide an endless device for training over cone pulleys or other analogous movable means, the belt will be prevented from stretching in view of the presence therein of the metal linked element 7, and furthermore, the complete belt organization is greatly strengthened and reinforced and as a consequence a belt organization is provided which will materially resist deterioration and wear,

In the event after long usage, the belt becomes worn, and particularly the base or contact element 5, the rawhide backing or element 6 may be detached from the worn element 5 and the latter replaced by another similar new device and the remaining parts of the belt associated therewith as shown, and thus economize in belt constructions of this character, and in fact wear on the joined portion of the links of the element 7 will be reduced to a minimum, and the rawhide backing element 6 not only shields the said element from exterior wear but of itself will be materially free from wear. The knuckle pivot members 9 of the several links serve as means for engagement by the rawhide backing element 6 and whereby the linked element 7 is held in central relation to the elements 5 and 6 as hereinbefore explained without interfering in the least with the movement of the links, to accommodate flexing of the belt as a whole, and furthermore, materially obstructing longitudinal shifting movement or loose action of the linked elements 7 between the two elements 5 and 6.

The improved belt organization may be made in any suitable lengths, and the primal preparation of the same or original association of the three main elements as specified may be effected at a small cost and by simple means. It should also be understood that the width and thickness of the improved belt may be modified to adapt the same to various applications and it is pro-

posed to use any suitable materials in making the elements 5 and 6, though leather and rawhide respectively are preferred in view of their natural durability and strength.

What is claimed as new is:

1. A belt of the class specified, comprising a base element, a backing element extending fully thereover throughout the length thereof, and a single interposed endless link belt retained centrally and loosely and extending the full length between the base and backing elements, the said link belt being prevented from moving laterally in either direction, the backing element being formed with a central bulged enclosing means for the link belt throughout the full length of the complete belt and permitting the endless link belt to move longitudinally within the enclosure thus formed.

2. A belt comprising a base element, a single longitudinal continuous link belt comprising movable parts joined at their extremities and disposed flat upon the base element, and a backing element secured at its side portions to the side edge portions of the base element and extending fully over and enclosing the single link belt and engaging portions of the joined extremities of the said element, the secured side edge portions of the backing element being rounded to present smooth surfaces, the backing element having a central bulged portion with downwardly inclined parts on opposite sides of the link belt for holding the latter in central position against lateral displacement yet movable longitudinally with the enclosure thus formed.

3. A belt comprising a base element, a backing element and an interposed reinforcing element consisting of an endless belt comprising a plurality of links pivotally connected at their extremities and disposed longitudinally between the base and backing element, the edge portions of the backing element being inturned and secured to the edge portions of the base element and the intermediate part of the backing element extending over and bearing upon the pivotally connected extremities of the links of the said reinforcing element and holding the latter in central position between the base and backing elements against lateral displacement but free to move longitudinally, the inturned edge portions of the backing element forming a non-catching side edge reinforcing thickness for the belt.

4. A belt of the class specified, comprising a base element for bearing on the curved surfaces of pulleys and the like, a backing element extending throughout the full length and width of the base element and secured at its edge portions to the corresponding portions of the base element, a space being formed between the base and backing elements by bulging the backing element and

including the same downwardly towards opposite side edges of the base element, and a reinforcing single endless belt consisting of a plurality of chain links having the ends 5 thereof pivotally joined, the intermediate portion of the backing element engaging portions of the pivoted ends of the said link members and holding the reinforcing belt

as a whole centrally in the said space and in longitudinal relation to the base and 10 backing elements against lateral movement but permitting longitudinal movement of the endless reinforcing belt.

In testimony whereof I have hereunto set my hand.

JAMES T. GRIFFIN.
